UNITED STATES PATENT OFFICE.

AUGUSTUS A. WEST, OF PHILADELPHIA, PENNSYLVANIA, ASSIGNOR TO WEST ELECTRIC HAIR CURLER COMPANY, OF PHILADELPHIA, PENNSYLVANIA, A CORPORATION OF DELAWARE.

DESIGN FOR A DISPLAY FRAME FOR ADVERTISING MATTER.

Application filed August 1, 1922. Serial No. 3,263. Term of patent 14 years.

To all whom it may concern:

Be it known that I, AUGUSTUS A. WEST, a citizen of the United States, residing in Philadelphia, Pennsylvania, have invented a new, original, and ornamental Design for a Display Frame for Advertising Matter, of which the following is a specification, reference being had to the accompanying drawing, forming part thereof, in which the figure is a front view of the display frame for advertising matter.

I claim:

The ornamental design for a display frame for advertising matter, as shown.

AUGUSTUS A. WEST.
